* cited by examiner

Primary Examiner — Karen E. Eldridge Powers*Assistant Examiner* — Kimberly Barnes*(74) Attorney, Agent, or Firm* — Baker & Hostetler LLP(57) **CLAIM**

We claim the ornamental design for a display screen with graphical user interface, as shown and described.

DESCRIPTION

The sole drawing FIGURE is a front view of a display screen with graphical user interface.

The broken lines in the drawing depicting a display screen and lettering illustrate environmental subject matter and form no part of the claimed design.
